United States Patent

Des. 238,859

Patented Feb. 17, 1976

238,859

INSTRUMENT FOR THE DISPLAY OF PROCESSED INFORMATION

Colin Simister Gaskell, Waresley, and Rory Morgan
O'Brien, Weston, England, assignors to Alfred Herbert
Limited, Coventry, England

Filed Apr. 17, 1974, Ser. No. 461,716

Claims priority, application Great Britain Oct. 22, 1973

Term of patent 14 years

Int. Cl. D10—04

U.S. Cl. D10—46

FIG. 1

FIG. 2

FIG. 3

FIG. 4

FIG. 5

FIG. 1 is a front elevational view of an instrument for the display of processed information, showing our new design;

FIG. 2 is a rear elevational view thereof;

FIG. 3 is a bottom plan view thereof;

FIG. 4 is a top plan view thereof;

FIG. 5 is a side elevational view thereof, the opposite side being a mirror image thereof.

We claim:

The ornamental design for an instrument for the display of processed information, substantially as shown and described.
